(57) **CLAIM**

I claim the ornamental design for a chewing tobacco can, as shown and described.

DESCRIPTION

FIG. 1 is an exploded perspective view of the tobacco can according to my new design;

FIG. 2 is a top plane view of the tobacco can of FIG. 1 on a reduced scale with the lid removed;

FIG. 3 is a top plane view of the tobacco can of FIG. 1 on a reduced scale with the lid on the can;

FIG. 4 is a side elevation view of the tobacco can of FIG. 1 on a reduced scale;

FIG. 5 is a bottom plan view of the tobacco can of FIG. 1 on a reduced scale; and,

FIG. 6 is an enlarged cross-sectional view of the tobacco can of FIG. 1 along a line 6 of FIG. 5.
